Primary Examiner — Paula Greene*(74) Attorney, Agent, or Firm* — NSIP Law(57) **CLAIM**

We claim the ornamental design for a headset, as shown and described.

DESCRIPTION

FIG. 1 is a front perspective view of a headset showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a second front perspective view in an alternate position thereof; and,

FIG. 9 is a third front perspective view thereof showing an example environment.

The broken lines in the figures show portions of the headset which form no part of the claimed design. The broken lines in FIG. 9 show portions of an example headrest which form no part of the claimed design.

1 Claim, 7 Drawing Sheets---
